UNITED STATES PATENT OFFICE

109,480

DESIGN FOR A SAFETY RAZOR CASE

Lewis W. Harlem, Quincy, Mass., assignor to American Traveling Goods Co., Inc., Boston,
Mass., a corporation of Massachusetts

Application February 21, 1938, Serial No. 75,299

Term of patent 3½ years

To all whom it may concern:

Be it known that I, Lewis W. Harlem, a citizen of the United States, residing at Quincy, in the county of Norfolk and Commonwealth of Massachusetts, have invented a new, original, and ornamental Design for a Safety Razor Case, of which the following is a specification, reference being had to the accompanying drawing, forming a part thereof.

In the drawing,—

Fig. 1 is a front elevational view of a safety razor case showing my new design in closed position;

Fig. 2 is a similar view showing the cover

flap opened in extension with the body of the case;

Fig. 3 is a side elevation of the case in the same condition in which it is shown in Fig. 2;

Fig. 4 is a side elevation of the case in the closed condition shown in Fig. 1.

Characteristic features of the design reside in the case as shown, having each of its ends provided with upwardly converging sides which merge at a point below the mouth of the bag.

I claim:

The ornamental design for a safety razor case as shown and described.

LEWIS W. HARLEM.
